Primary Examiner — Cynthia E Ramirez(74) *Attorney, Agent, or Firm* — Wells St. John PS(57) **CLAIM**

I claim the ornamental design for an article transport vehicle, as shown and described.

DESCRIPTION

FIG. 1 is a front perspective view for an article transport vehicle;

FIG. 2 is a front elevational view thereof;

FIG. 3 is a rear elevational view thereof;

FIG. 4 is a side elevational view thereof;

FIG. 5 is a side elevational view, opposite the FIG. 4 side view, thereof;

FIG. 6 is a top plan view thereof; and,

FIG. 7 is a bottom plan view thereof.

The broken line showing of tanks in FIG. 1 is included for the purpose of illustrating environment and forms no part of the claimed design.
